Primary Examiner — George D. Kirschbaum*Assistant Examiner* — Antoinette Martine Suiter(74) *Attorney, Agent, or Firm* — Suzanne Kikel(57) **CLAIM**

The ornamental design for a gap gauge, as shown and described.

DESCRIPTION

FIG. 1 is a top, left perspective view of a gap gauge arranged between panels of an automobile, showing my new design; FIG. 2 is a left, side perspective view of the gap gauge of FIG. 1 removed from between the panels of an automobile; FIG. 3 is a right, side perspective view of the gap gauge of FIG. 2; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

The broken line showing of the panels of an automobile in FIG. 1 forms no part of the claimed design.

1 Claim, 9 Drawing Sheets(56)
